FIG. 9

METHOD OF DRIVING THE GEARING OF AN ELECTRONIC TIMEPIECE AND AN ELECTRONIC TIMEPIECE FOR IMPLEMENTING SAID METHOD

In electronic timepieces the time base of which is constituted by a high-stability electronic oscillator, for example a crystal-controlled oscillator, the actual time display is often effected by mechanical means.

In situations where these timepieces must not only have particularly small dimensions in order to be carried by the user, and this is especially the case where electronic wristwatches are concerned, the electromechanical transducer used in such watches has to satisfy a number of requirements which are specifically:

because of the small amount of electrical energy which it is possible to periodically supply to the transducer, the latter must operate with a particularly high degree of efficiency;

the reliability of operation of the transducer should be relatively high if errors in the time display produced by said transducer, are not to cancel out the benefits derived from the use of a particularly accurate time base

the transducer should be insensitive to external disturbances to which the timepiece may be subjected (shocks, magnetic fields, etc.).

The object of the present invention comprises a method of driving the gear train of an electronic timepiece, and also an electronic timepiece for implementing said method, by means of which it is possible to obtain a time display or indication which satisfies the above conditions.

This method is characterized in that each tooth of one of the gears of the gear train successively receives an impact and of that the angular displacement in the gear, as a consequence of each impact is limited to a predetermined value.

The electronic timepiece for implementing said method comprises a device for indicating the time, which device includes a gear train and a time indicator controlled by said gear train, an electronic circuit producing periodic signals of a predetermined frequency, and an electromechanical transducer for driving said device, which transducer is controlled by the signals produced by said circuit, wherein said transducer incorporates a member which swings periodically, at the frequency of said signals, between two limiting positions in order, at least once during the course of two successive swings, to strike successively each tooth of a gear in the gear train, and means being provided in order to limit to a predetermined value the angular displacement of the gear as a consequence of each impact.

The attached drawing illustrates by way of example an embodiment of an electronic timepiece for implementing the method forming the object of the present invention:

FIG. 1 is a schematic view showing part of the elements of said timepiece;

FIG. 2 is an elevational view;

FIGS. 3, 4, 5 and 6 are detailed views illustrating various phases of operation of an electromechanical transducer of the kind fitted to the timepiece of FIG. 1;

FIGS. 7 and 8 are explanatory diagrams;

FIG. 9 is a detailed view of a modification of one of the timepiece elements.

The electronic timepiece illustrated in the drawing (FIGS. 1 and 2), comprises a high-precision oscillator B, for example a crystal-controlled oscillator producing a periodic high-frequency signal, an electronic scaler D capable of dividing the frequency of said signal, for example down to a value of 1 Hz., and a circuit ER controlled by said scaler and designed to supply periodic pulses to an electromechanical transducer in order to drive the second wheel S of a gear train schematically represented by the axis A in order to control the hands H of the timepiece.

This transducer comprises an anchor-shaped moving armature 1 keyed to a spindle 2 which is pivoted at each end in jewels 3 and 4 illustrated schematically in the drawing, said spindle carrying two hubs 5 and 6 for the attachment of two

spiral springs 7 and 8, and arm 9. These hubs are made, the first, of metal and the second, of electrical insulating material.

Secured to the armature 1 there is a coil 10 electrically connected to the spiral spring 7 by a connection 10a, soldered to the spindle 2, and by this spindle, to the spiral spring 8 by another connection 10b, said plate extending in the plane of said armature between two U-shaped permanent magnets 11 and 12, which face one another with their open ends and are fixed to a mounting plate which has not been shown.

Each magnet comprises two pole pieces 11a and 11b (FIG. 1) made of ferromagnetic material having a very high coercive field strength, the pole pieces being connected to one another by a yoke 11c of magnetizable material having a low coercive field strength and high permeability.

The electromechanical transducer described is of the monostable kind and its armature 1 is biased into the position illustrated in FIG. 1, by the two spiral springs 7 and 8. As the illustration shows, the magnets 11 and 12 are positioned so that, taking into account their dimensions and in particular the cross-sectional area of their pole pieces, the turns of the coil are intersected by a maximum magnetic flux over the whole extent of the angular travel of the armature 1. This flux is, moreover, particularly strong in view of the fact that the magnets 11 and 12 are for the most part made of material having a high magnetic energy and a high coercive field strength, and that the ratio of the length of the magnets to the width of the airgap within which the coil moves, is relatively large.

If an external field were superimposed upon the magnetic field produced by the magnets 11 and 12, this parasitic field would have no direct influence upon the driving of the armature 1 and, therefore, on that of the gear train of the timepiece. In order to exert a disturbing effect on the coil 10, such a parasitic field would have to be orientated in a predetermined direction over one-half of the coil width and in the opposite direction over the other half. In view of the very small dimensions of the coil 10, amounting to some few millimeters in diameter only, for example, it is virtually out of the question for any parasitic field to satisfy the above condition.

The result is that the electromechanical transducer illustrated, is virtually completely insensitive to the effect of magnetic fields occurring externally of the timepiece. However, this advantage is not the only one deriving from the above arrangement, as will be appreciated from the ensuing description.

The spiral springs 7 and 8 are coiled in opposite directions and their external extremities, secured by conventional means to a balance cock (not shown) are connected electrically, in the case of the coil spring 7, to the circuit ER, and in the case of the coil spring 8, to earth, while the jewel bearings 3 and 4 are assembled in insulating housings which have not been shown.

Because the hub 5 to which the coil spring 7 is attached is made of metal and is secured to the spindle 2 and the hub 6 is made of an insulating material so that there is no electrical connection between the spiral spring 7 and the spiral spring 8, the pulses produced by the circuit ER are supplied to the coil 10 through the spring 7 and then pass to earth through the spring 8.

The arm 9 is designed to limit the pivoting movement of the armature by cooperation with two stops 13 and 14 secured to the bridge on the backing plate (not shown), the stop 14 being the exit one, against which the arm 9 abuts when the armature 1 is in the rest condition, and the stop 13 being the entry one, against which the arm strikes when it is swung in the direction F at the same time as the armature 1 (FIG. 1).

It is worthy of mention that the spiral springs 7 and 8 are lightly loaded when the various moving elements of the transducer are in the position illustrated in FIG. 1, so that the arm 9 is applied lightly against the stop 14.

The driving of the seconds wheel or gear S of the movement is produced exclusively by the alternate striking of the pallets 1a and 1b of the armature 1, against the different teeth 15 of the wheel or gear, in the manner now to be described in relation to FIGS. 1 to 6.

This drive system is particularly relevant to the case where energy transmission is to be effected with maximum efficiency, and in particular where the amount of energy which can be supplied to the coil 10 with each pulse from the circuit ER, is small. In other words, this method of driving by a single mechanical impulse, overcomes all the defects and drawbacks traditionally associated with drive systems which employ friction between components, i.e. a quantity the value of which varies very widely and depends upon the condition of the surfaces involved and upon their changing characteristics with time and wear etc.

The transmission of energy by the striking of a driving element against a driven element, on the other hand, is determined exclusively by the geometrical dimensions of the moving parts and by the respective moving masses. As far as the losses involved in the transmission of energy by impact, are concerned, those skilled in the art will understand that these depend primarily upon the elastic properties of the materials directly involved in said transmission, and not upon the mechanical condition of the surfaces which come into contact with one another. In any case, if this surface condition was wrong after commencement of energy transmission by impact, it will improve very rapidly by consequence of repeated hammer blows between the surfaces involved, so that the energy transmission factor between drive element and driven element will be improved likewise.

It should be pointed out, nevertheless, that in the case of energy transmission by impact of a pivoting element, such as the armature 1, against the second rotary element, in the present instance the seconds wheel S, the efficiency with which said energy transmission takes place achieves a maximum only when the impact takes place in a direction which is tangential, at the point of impact, to the trajectory which is followed, after the impact, by that part of the said element which receives the impact. In the present instance, the second moving body is a toothed wheel and accordingly said trajectory will be circular.

However, when using a toothed wheel, it is virtually out of the question to achieve this ideal condition, since each tooth preceding the one intended to be struck by the armature 1, or more particularly by the pallets 1a and 1b, presents an obstacle to said armature, and prevents the striking action taking place.

However, it can be shown that it is possible to obtain an energy efficiency equivalent to the ideal efficiency above defined, even if the impact does not take place tangentially to the circular trajectory followed by the different teeth of the seconds wheel but rather by the impact takes place normally to said trajectory, provided that the striker element, i.e. one or the other of the pallets with which the armature 1 is fitted, has a striker face which, like that part of the tooth which is involved in the impact, makes an angle of 45° with the tangent (taken at the point of impact of the former against the latter), to the circular trajectory followed by this part of the tooth after impact.

In the case of the transducer shown in FIG. 1, the position of the center of pivoting of the armature 1, the length of those arms of said armature which carry the pallets 1a and 1b, and the angular position of each pallet on its respective arm, have accordingly been chosen so that in the position of approach, each pallet is directed towards the center of pivoting of the wheel S when it hits said wheel. In addition, the end of the pallet is profiled in order to make an angle of 45° with the tangent to the circular trajectory followed by the different teeth of the wheel S.

The efficiency of the impulse driving system employed in respect of the gearing system of the timepiece, the impulse being applied to the seconds wheel S (FIG. 1 and FIG. 2) by the pallets 1a and 1b of the transducer armature, can be defined in terms of the ratio of the kinetic energy stored by the gear train and by the indicating hands of the timepiece, after the impact, to that stored by the moving part of the electromechanical transducer prior to said impact, viz:

$$\eta = \frac{\theta \cdot \omega_R'^2}{\theta \cdot \omega_S^2}$$

where θ is the moment of inertia of the moving part of the transducer, that is to say the assembly comprising the spindle 2, the hubs 5 and 6, the coil springs 7 and 8, the armature 1 and the coil 10;

ω_S is the angular velocity of said arrangement at the time of impact of the pallet 1a against a tooth of the wheel S;

θ_R is moment of inertia of the gearing system and the indicator hands, with reference to the center of rotation of the seconds wheel S;

ω'_R is the angular velocity with which the wheel S rotates after having been hit by one of the pallets of the transducer.

If the impact of each pallet of the armature against the teeth of the wheel S takes place when said pallet is moving towards the center of rotation of the wheel, in the manner described, and if both the striker face of the pallets and that of the teeth of the wheel, are profiled in the manner described so that in both cases they are contained in a common plane inclined at 45° to the tangent (considered at the point of the teeth) to the circular trajectory of the zone of impact, then the efficiency equation defined above can equally well be written:

$$\eta = \frac{(1+k)^2}{\left[\sqrt{\frac{\theta}{\theta_R} \cdot \left(\frac{r_A}{r_a} \right)} + \frac{1}{\sqrt{\frac{\theta}{\theta_R} \cdot \left(\frac{r_A}{r_a} \right)}} \right]^2}$$

in which formula

k is the "recovery" coefficient which can have a value somewhere between 0 and 1 and is defined by the ratio of the velocity reached by an element of a given material after having fallen onto a fixed substrate likewise made of a given material but possibly of different nature, and the velocity which said same element had prior to hitting the substrate;

r_a is the effective radius of the driving element, that is to say the distance separating the center of pivoting of the armature 1, and the striker face of one or other of the pallets;

r_A is the effective radius of the driven element, that is to say the distance separating the center of pivoting of the seconds wheel S and the impact-receiving face of each tooth;

θ and θ_R have the same significance as that hereinbefore defined.

For a given value of k , this efficiency is maximum when:

$$\frac{\theta}{\theta_R} \cdot \left(\frac{r_A}{r_a} \right)^2 = 1 \text{ or } \frac{\theta}{\theta_R} = \left(\frac{r_a}{r_A} \right)^2$$

in other words when the moments of inertia of the moving element are in the ratio of the square of the respective effective radii of said components.

In addition, as in the present instance, velocities ω'_R and ω_S are relatively small and, taking into account the materials which can be used for the elements involved in the impact, it is possible to obtain a transmission coefficient k having a value quite close to 1, and this indicates that the impact which takes place is essentially elastic in nature.

It follows from the efficiency equation hereinbefore defined that, in the case where

$$\frac{\theta}{\theta_R} \cdot \left(\frac{r_A}{r_a} \right)^2 = 1$$

said efficiency can reach values close to unity so that energy transmission by impact is obviously of particular significance in the context of clock systems.

In order to ensure that on the occasion of impulse-energy transmission from one moving element to another, it shall be possible nevertheless to achieve friction between the first and second elements, in particular after the impact, it is essential that the velocity of the striker element after impact should become zero or negative in relation to the velocity which it had prior to impact.

In the case of the armature 1 described, and which approaches the wheel S by displacement of its pallets in the direction which is radially disposed in relation to said wheel, it can be shown that the angular velocity ω'_S of the assembly of spindle 2, hubs 5 and 6, spiral springs 7 and 8, armature 1 and coil 10, after the impact of a pallet 1a OR 1b of the armature

against one of the teeth of the wheel S, satisfies the relationship

$$\omega'_s = \omega_s \left[1 - \frac{1+k}{1 + \frac{\theta}{\theta_R} \left(\frac{r_A}{r_a} \right)^2} \right]$$

in which ω_s is the angular velocity of said same assembly *before* the impact, k , θ , θ_R , r_A and r_a being the same quantities as hereinbefore defined.

If $\omega'_s = 0$, then this relationship becomes

$$1+k = 1 + \frac{\theta}{\theta_R} \frac{r_A^2}{r_a^2}$$

from which we obtain

$$\frac{\theta}{\theta_R} \frac{r_A^2}{r_a^2} = k$$

and

$$\frac{\theta_R}{\theta} \left(\frac{r_a}{r_A} \right)^2 = \frac{1}{k}$$

By introducing one or other of these values into the efficiency equation for η , defined hereinbefore as a function of k , θ , θ_R , r_a and r_A , it is evident that it, the moving parts of the electromechanical transducer, should become still after the impact, ($\omega'_s = 0$), the efficiency of energy transmission is to reach the value

$$\eta = k.$$

If k has a value close to unity, said efficiency has the maximum value of unity hereinbefore referred to and the expression

$$\frac{\theta}{\theta_R} \left(\frac{r_A}{r_a} \right)^2 = \frac{1}{k}$$

becomes equal to unit in the manner hereinbefore described.

In practice, it is sometimes difficult to achieve an electromechanical transducer and a gear train, in particular a seconds wheel S, which accurately satisfy the above conditions, either because the manufacture and assembly of the various elements cannot be effected with the necessary accuracy or because, in order to facilitate manufacture, one is forced to depart slightly from the theoretical values both as far as the slope which the tips of the pallets or the flanks of the teeth of the seconds wheel, should have, or as far as the movement of inertia θ or θ_R is concerned.

The efficiency of the overall timepiece mechanism depends also upon the method by which the electrical energy of the pulses periodically supplied to the transducer R, is converted into mechanical energy to drive the armature.

The efficiency of an electrodynamic transducer is proportional, on the one hand, to the mean velocity of displacement of the armature 1 and all the moving parts associated therewith, i.e. the drive coil and, on the other hand, and for a given supply voltage, to the mean flux across the coil 10 during the drive phase. It will be understood by those skilled in the art that it is, under these circumstances, to arrange for the mean velocity of the armature of the transducer to be very high and for the magnetic field produced by the magnets 11 and 12 to have a particularly high value. It is precisely because it is desirable to enable the armature 1 to be accelerated very rapidly, that is has been chosen to make the coil 10 mobile and the magnets 11 and 12 fixed. In addition, despite the small size of the transducer, the magnetic flux produced is particularly strong, these magnets being made of a ferromagnetic material having high coercive field strengths. In addition, the magnets have a relatively large volume in relation to the volume of the airgap between them, the coil 10 moving through said airgap in the manner described.

In the rest condition, the moving elements of the transducer thus occupy the position shown in FIGS. 1 and 2, abutting against the stop 14 through the medium of the arm 9 under the action of the torque exerted by the two spiral springs 7 and 8. This torque will be made sufficiently large to ensure that even

the most intense disturbing accelerations at which a watch can be submitted, in normal use conditions, could be not sufficient to tilt the armature 1 in such a manner that the pallet 1a could strike against a tooth of the wheel S.

- 5 If, on the other hand, the moving elements of the transducer are in fact moving, and a disturbing acceleration takes place, the effect of this acceleration will vary depending upon whether it is the direction F or in the opposite direction. In the first instance, the disturbing acceleration will sustain the movement of the armature 1 which is being driven by the occurrence of a pulse in the coil 10, and this does not constitute any nuisance; in the second case, the acceleration will be opposed to the movement and, if required, may inhibit contact between the pallet 1a and a tooth of the wheel S. In order to render the operation of the transducer as far as possible insensitive to external shocks, it is therefore essential to arrange that the kinetic energy imparted to the moving elements of said transducer by the torque resulting from the combined action of the coil 10 and the magnets 11 and 12, is as large as possible, ensuring that the mean velocity of displacement of these elements is high. Of course, since the time of displacement of the moving elements in each direction of swing is very short, the period of time for which such a disturbing acceleration could be effective, will be very short indeed.

When the electromechanical transducer is in the rest condition, the armature 1 occupies the position shown in FIGS. 1 to 3: As FIG. 3 illustrates in detail, the pallet 1b of the armature is then engaged between two teeth of the wheel S and locks 30 the latter against angular movement and accordingly the remainder of the gear system of the timepiece too.

As soon as a pulse arrives from the circuit ER in the coil 10, the armature is accelerated in the direction F until the pallet 1a hits the striker face b of a tooth d_1 of the wheel S (FIG. 4), 35 with its own striker face a. The result is that the major parts of the kinetic energy stored in the moving elements of the transducer is transmitted to the wheel S which then displaces in the direction F_1 until the tooth d_2 which was initially struck, clears the pallet 1a. The position of the latter pallet at this instant is determined by contact between the arm 9 (FIG. 1) and the stop 13.

The spiral springs 7 and 8 are fully tensioned and exert a returning force on the armature 1 in the direction F_2 , so that said armature is swung back towards the left (considered in the drawing) until the pallet 1b clears the tooth d_3 , the wheel S then experiencing an impact which transfers a new quantity of kinetic energy to it, moving it in the direction F_1 until the pallet 1b enters the space defined between said tooth d_3 and the following tooth d_4 . The arm 9 which limits the movement, then 50 hits the stop 14.

The above process then starts all over again with the arrival at the transducer R of a new electrical pulse, and so on.

As FIGS. 5 and 6 show, the first impact on the tooth d_1 of the wheel S, simply advances said wheel by a distance corresponding substantially to the length of a tooth pitch, reduced by the width of the pallet 1a (FIGS. 4 and 5), while the second impact, against the tooth d_3 , causes the wheel to advance by a value equivalent to the width of the pallet 1b (FIGS. 6 and 3) so that overall, the wheel S is moved a distance equivalent to a tooth pitch with each electrical pulse received by the electromechanical transducer.

It is a similar situation which is depicted in FIG. 7, the latter illustrating, as a function of time, how the angular velocity ω_s of the armature 1 varies each time the electromechanical transducer receives a pulse i , and how the angular displacement Φ of the wheel S due to the impulse which it periodically receives, takes place.

In particular, it will be observed that the velocity ω_s rises to a maximum ω_1 as long as the pulse lasts, dropping rapidly to zero at the instant t_1 at which the impact of the pallet 1a occurs, after which instant the wheel S commences to move, the armature and the wheel then occupying the position shown in FIG. 4. The displacement of the wheel S takes place over an angular interval Φ_1 up to the time t_2 , that is to say up to the

time at which the tooth d_2 following the one just hit, comes into contact with the pallet $1a$ of the armature 1 (FIG. 5), the latter commencing to move in the direction F_2 under the action of the spiral springs 7 and 8 . The velocity of said armature, which is reduced substantially to zero between the times t_1 and t_2 and which has risen to a value ω_2 , drops off suddenly down to a value ω_3 at the instant t_3 at which the pallet $1b$ of the armature hits the tooth d_3 of the wheel S (FIG. 6). After this instant t_3 , the wheel S commences to move through an angular interval equivalent to $\Phi_2 - \Phi_1$, the factor Φ_2 corresponding to a tooth pitch, until the tooth d_4 of the wheel clears the pallet $1b$ of the armature (instant t_4), this pallet having penetrated into the space separating the teeth d_3 and d_4 . As FIG. 7 shows, the angular velocity ω_s of the armature 1 which had dropped to ω_3 at the time of impact, has increased slightly thereafter to a value ω_4 , only to drop to zero at the instant t_5 which corresponds to the time at which the armature reverts to the position shown in FIG. 1, in contact with the stop 14 through its arm 9 .

The number of teeth on the wheel S is of the order of 60 and the frequency of the pulses coming from the circuit ER is of the order of 1 Hz., so that the seconds hand of the timepiece, which is associated with this wheel, indicates the advance in time of 1 second with each swing of the armature 1 , i.e. with each pulse.

The general arrangement of the armature 1 , the pallets $1a$ and $1b$, and the toothing of the wheel S , is such that said wheel is never free to move in the angular sense during that part of the swinging movement of the armature which precedes and follows each impulse or impact, the pallets of the armature being alternately in engagement with the toothing.

As hereinbefore described, the electromechanical transducer of the timepiece is of the monostable kind so that the driving of the armature 1 is effected by pulses of the same polarity. Although this method of driving means that said pulses can be produced in a simple manner, since they can be obtained from the output of a binary scaler for example, it nevertheless gives rise to a mechanical drawback for the following reasons: After the first impact between armature and wheel, the armature loses speed, in fact it may even come to a halt, and is then simply subject to the restoring couple developed by the spiral springs 7 and 8 . On the other hand, the toothed wheel has received virtually all the momentum energy of the armature so that it is displacing rapidly. The result is that the next tooth of the wheel, i.e. the one following the one just struck by the entry pallet of the armature, may hit said pallet before the latter has been able to clear the circular trajectory described by the tips of the teeth (see FIG. 5).

It goes without saying that this kind of impact must be avoided, since it in no way contributes to the correct operation of the timepiece.

Moreover, this kind of impact can, under certain circumstances and by virtue of a rebound effect on the part of the wheel S , return the wheel to its initial position so that the timepiece is slow.

It is possible to overcome this drawback by adding to the circuit ER a differentiating circuit of the RC kind, which converts each rectangular waveform pulse i (FIG. 8), into a train of two pulses I_1 and I_2 of mutually opposite polarity.

For this method of driving, the electromechanical transducer of the timepiece described, remains exactly the same as illustrated in FIGS. 1 and 2 as far as its general structure is concerned, although it will be understood that from the electromechanical point of view it will be modified as compared with the system employed in the case where strictly rectangular waveform pulses are used, as for example the pulses i (FIG. 8).

In other words, although the acceleration of the armature 1 under the effect of the pulse I_1 , the latter for example of positive polarity, takes place normally, the situation is slightly different as far as the phase of return of the armature to the rest position, after the impact of the pallet $1a$ of the tooth d_1 (FIG. 4) under the action of the spiral springs 7 and 8 , is concerned. 70

Specifically, the armature 1 , which is virtually at a standstill after the impact, is then not only driven backwards by the spiral springs but also by the effect of the negative polarity pulse I_2 . The result is that the armature is accelerated back into the rest position much faster than it would be under the sole effect of the spiral springs 7 and 8 , and that as a consequence the pallet $1a$ can be withdrawn from the gap between the tooth d_1 and the tooth d_2 before the latter hits it, so there is no longer any loss of energy from the wheel S of the kind which would otherwise occur if there was contact between it and the armature 1 . Thus, by appropriately dimensioning the moving elements of the transducer, including the spiral springs, the gearing of the timepiece and the differentiating circuit associated with the circuit ER , it is possible to arrange that the sole contacts which take place between the pallets $1a$ and $1b$ and the teeth of the wheel S , are ones during which energy is transferred to said wheel by impact with the pallets, said transmission thus being effected with a particularly high efficiency.

20 It is likewise possible, in accordance with a variant embodiment illustrated in FIG. 9, to prevent the blocking of the seconds wheel, S by contact between the tooth d_2 and the pallet $1a$ after the striking of the preceding tooth, by cutting the end of said pallet in such a manner as to produce a face e which makes an angle of 90° with the face a already described, said face e being designed to undergo contact with the tip of the tooth d_2 when the wheel S is moving in the direction F_1 under the effect of the impact which has previously taken place with its tooth d_1 . This recovery of energy by the armature 1 from the wheel S is sufficient to accelerate the former rapidly back into its stable position. In the case of this variant embodiment, the drive pulses may take a rectangular form in the manner of the pulses i shown in the diagram V of FIG. 7.

25 A similar effect can equally well be achieved by employing a transducer similar to the one shown in FIGS. 1 and 2, in particular as far as the general form of its elements (notably the pallet $1a$ and $1b$ and the teeth of the wheel S) are concerned, and also as far as the method of supply of periodic pulses i is concerned, by dimensioning the moving elements of the transducer and the gearing arrangement in order that the velocity ω_s of the armature after impact is not zero but slightly negative in relation to the velocity ω_s which it has prior to impact.

30 Returning to the expression hereinbefore referred to and defining ω_s as a function of ω_s , k , θ , θ_R , r_A and r_a , we can then write

$$\omega_s \cdot \left[1 - \frac{1+k}{1 + \frac{\theta}{\theta_R} \cdot \left(\frac{r_A}{r_a} \right)^2} \right] = \omega_s' < 0$$

50 from which we obtain

$$\frac{\theta_R}{\theta} \cdot \frac{r_a^2}{r_A^2} > \frac{1}{k}$$

55 so that if, for a given k value, the various geometric quantities θ_R , θ , r_a , r_A are chosen in order to satisfy this equation, the armature 1 will rebound slightly after impact between the pallet $1a$ and the tooth d_1 of the wheel S , and this will increase the angular velocity given to said armature by the action of the spiral springs 7 and 8 , in its movement in direction F_2 .

In addition to the qualities which any electromechanical transducer should exhibit, and which have been referred to hereinbefore, the transducer used in the timepiece described exhibits the following advantages:

60 the positioning of the moving elements of the electromechanical transducer takes place in such fashion that said elements are maintained in a single stable state so that the method by which the transducer is electrically driven becomes particularly simple; the driving of the gear train is in a step-by-step manner at a very low frequency (1 Hz. for example), and this makes it possible to design a mechanical section of the transducer to have dimensions and an accuracy which are, to an order of magnitude, compatible with those of conventional timepieces.

Finally, although the present description and the attached drawings have simply dealt with the case of the impulse-driving of the gearing of a timepiece by action upon the seconds wheel of said gearing, saying it would equally be possible to achieve this same drive function by impulse operation of another moving part of said gearing, it being understood that drive pulses of an appropriate frequency would have to be provided.

I claim:

1. An electronic timepiece, comprising a device for indicating the time, which device includes a gear train and a time indicating device controlled by said gear train, an electronic circuit which produces periodic signals of a predetermined frequency, and an electromechanical transducer for driving said device, which transducer is controlled by the signals produced by the said circuit, wherein said transducer incorporates a member which swings periodically and at the frequency of said signals, between two limiting positions in order, at least once during the course of two successive swings, to strike successively each tooth of a gear in the gear train, means for limiting to a predetermined value the angular displacement of the gear as a consequence of each impact, said member comprises elements, one of said elements striking the teeth of said gear and following a radial trajectory in relation to said gear at the point of impact, the impact-applying surface of said element and the impact receiving of each tooth of the gear at the time of impact, being contained in a common plane making an angle substantially 45° with a tangent at the center of the zone of impact of the member which strikes against the tooth to the circular trajectory followed by the center of the impact zone on the tooth during the rotary motion imparted to the gear by the impact.

2. A timepiece as claimed in claim 1, wherein said member and said time-indicating device are so dimensioned that the moment of inertia (θ) of the member and that of the moving parts of said device (θ_R), with reference to the center of rotation of the gear, the distance (r_a) separating the zone of impact of said member from its pivot, and the distance (r_A) separating the zone of impact on each tooth of said gear from its center of rotation, substantially satisfy the equation

$$\frac{\theta_R}{\theta} \left(\frac{r_a}{r_A} \right)^2 = \frac{l}{k}$$

in which k is the coefficient of restoration at impact.

3. A timepiece as claimed in claim 2, wherein the electromechanical transducer is of the monostable kind; and wherein said member comprises an anchor-shaped armature supporting a pair of pallets each of which acts as a hammer for applying an impact to the teeth of said gear and hits each tooth of said gear in succession, firstly when said armature is moving into its unstable limiting position, and secondly when as it returns to its stable limiting position, the extremity of each pallet being profiled to form said surface of said member which strikes the teeth of the gear, and wherein at least one spiral spring is associated with the armature to return said armature into its stable position each time it has moved away therefrom.
4. A timepiece as claimed in claim 3, wherein said limiting means are constituted, by each pallet of the armature and by the space separating the teeth of the gear, the pallets penetrating into said space when the armature is in its stable limiting position and when said armature is in its second, unstable limiting position.
5. A timepiece as claimed in claim 4, wherein said member and said time-indicating device are so dimensioned that, the moment of inertia (θ) of said member and that (θ_R) of the moving parts of said device with reference to the center of rotation of the gear which is subjected to the impact and the distance (r_a) separating the point of impact of said member from its pivot, and the distance (r_A) separating the center of the zone of impact on each tooth of the gear from the center of rotation thereof, satisfy the relationship

$$\frac{\theta_R}{\theta} \left(\frac{r_a}{r_A} \right)^2 > \frac{l}{k}$$

6. A timepiece as claimed in claim 4, wherein said pallet of the armature which strikes the tooth of the gear when said device is moving into its unstable limiting position, has a second face adjacent the impact applying surface of said element, which second face is substantially perpendicular to the plane of said applying surface.

7. A timepiece as claimed in claim 4, comprising an RC differentiating circuit connected between the electronic circuit and the electromechanical transducer, said differentiating circuit producing a train of two pulses having mutually opposite polarities, in respect of each periodic signal received by the electronic circuit.
